DESIGN FOR A COMBINED DISPENSER AND CLOSURE FOR A CONTAINER

Edward Richard Haemac, Hollywood, Calif., assignor to Na-Mac Products Company, a corporation of California

Application October 8, 1938, Serial No. 80,319

Term of patent 14 years

To all whom it may concern:

Be it known that I, Edward R. Haemac, a citizen of the United States, residing at Hollywood, in the county of Los Angeles and State of California, have invented a new, original, and ornamental Design for a Combined Dispenser and Closure for a Container, of which the following is a specification, reference being had to the accompanying drawing, forming a part thereof.

In the drawing:

Fig. 1 is a perspective view of a combined dispenser and closure for a container embodying my new design, the container being shown in dotted lines.

Fig. 2 is a side view thereof and

Fig. 3 is a top plan view.

I claim:

The ornamental design for a combined dispenser and closure for a container, substantially as shown and described.

EDWARD RICHARD HACMAC.
